UNITED STATES PATENT OFFICE

101,128

DESIGN FOR AN AERIAL

Benjamin Rex Lonsford, Borger, Tex.

Application December 16, 1935, Serial No. 60,114

Term of patent 3½ years

To all whom it may concern:

Be it known that I, Benjamin Rex Lonsford, a citizen of the United States, residing at Borger, in the county of Hutchinson and State of Texas, have invented a new, original, and ornamental Design for an Aerial, of which the following is a specification, reference being had to the accompanying drawing, forming part thereof.

Figure 1 is a view in side elevation of an aerial showing my new design.

Figure 2 is an enlarged front elevational view thereof with a portion of the supporting member broken away.

I claim:

The ornamental design for an aerial as shown.
BENJAMIN REX LONSFORD.
